DISPENSING CAP FOR PRESSURIZED CONTAINERS

William M. Goldsmith, Highland Park, Ill., assignor to Simoniz Company, a corporation of Delaware

Filed Nov. 5, 1963, Ser. No. 77,294

Term of patent 14 years

(Cl. D58—26)

FIG. 1 is a top plan view of a dispensing cap for pressurized containers embodying my new design;

FIG. 2 is a side elevational view thereof;

FIG. 3 is a rear elevational view thereof; and

FIG. 4 is a front elevational view thereof.

The portions shown in broken lines are for illustrative purposes only.

I claim:

The ornamental design for a dispensing cap for pressurized containers, as shown and described.
